(57) **CLAIM**

The ornamental design for a flag, as shown and described.

DESCRIPTION

This patent application is also related to U.S. patent application Ser. No. 17/738,103, filed on May 6, 2022, the disclosures of which are both herein incorporated by reference.

FIG. 1 is a perspective view of a first embodiment of a flag showing my new design;

FIG. 2 is front side view of the flags of FIG. 1, the back side being a mirror image thereof;

FIG. 3 is a right side view of the flag of FIG. 1, the left side being a mirror image thereof;

FIG. 4 is top view of the flag of FIG. 1;

FIG. 5 is a bottom view of the flag of FIG. 1;

FIG. 6 is a perspective view of a second embodiment of a flag showing my new design;

FIG. 7 is a front side view of the flags of FIG. 6, the back side being a mirror image thereof;

FIG. 8 is a right side view of the flag of FIG. 6, the left side being a mirror image thereof;

FIG. 9 is a top view of the flag of FIG. 6;

FIG. 10 is a bottom view of the flag of FIG. 6;

FIG. 11 is a perspective view of a third embodiment of a flag showing my new design;

FIG. 12 is a front side view of the flag of FIG. 11, the back side being a mirror image thereof;

FIG. 13 is a right side view of the flag of FIG. 11, the left side being a mirror image thereof;

FIG. 14 is a top view of the flag of FIG. 11;

FIG. 15 is a bottom view of the flag of FIG. 11;

FIG. 16 is a perspective view of a fourth embodiment of a flag showing my new design;

FIG. 17 is a front side view of the flag of FIG. 16, the back side being a mirror image thereof;

(Continued)

FIG. 18 is a right side view of the flag of FIG. 16, the left side being a mirror image thereof;
 FIG. 19 is a top view of the flag of FIG. 16;
 FIG. 20 is a bottom view of the flag of FIG. 16;
 FIG. 21 is a perspective view of a fifth embodiment of a flag showing my new design;
 FIG. 22 is a front side view of the flag of FIG. 21, the backside being a mirror image thereof;
 FIG. 23 is a right side view of the flag of FIG. 21, the left side being a mirror image thereof;
 FIG. 24 is a top view of the flag of FIG. 21;
 FIG. 25 is a bottom view of the flag of FIG. 21;
 FIG. 26 is a perspective view of a sixth embodiment of a flag showing my new design;
 FIG. 27 is a front side view of the flags of FIG. 26, the back side being a mirror image thereof;
 FIG. 28 is a right side view of the flag of FIG. 26, the left side being a mirror image thereof;
 FIG. 29 is a top view of the flag of FIG. 26;
 FIG. 30 is a bottom view of the flag of FIG. 26;
 FIG. 31 is a perspective view of a seventh embodiment of a flag showing my new design;
 FIG. 32 is a front side view of the flag of FIG. 31, the back side being a mirror image thereof;
 FIG. 33 is a right side view of the flag of FIG. 31, the left side being a mirror image thereof;
 FIG. 34 is a top view of the flag of FIG. 31; and,
 FIG. 35 is a bottom view of the flag of FIG. 31.
 The broken lines in the drawings represent portions of the flag and form no part of the claimed design. The other broken lines in FIGS. 1, 6, 11, 16, 21, 26 and 31 represent environmental subject matter only and form no part of the claimed design.

1 Claim, 35 Drawing Sheets
